J. V. KRANEBIEL.

OIL BURNER.

APPLICATION FILED OCT. 10, 1918.

1,324.507.

Patented Dec. 9, 1919.

UNITED STATES PATENT OFFICE.

JOHN V. KRANEIEL, OF WILLIAMSVILLE, NEW YORK.

OIL-BURNER.

1,324,507.

Specification of Letters Patent.

Patented Dec. 9, 1919.

Application filed October 10, 1918. Serial No. 257,649.

To all whom it may concern:

Be it known that I, JOHN V. KRANEIEL, a citizen of the United States, residing in Williamsville, in the county of Erie and State of New York, have invented new and useful Improvements in Oil-Burners, of which the following is a specification.

This invention relates to an oil burner which is more particularly designed for utilizing kerosene oil as a fuel for heating purposes, although the same, if desired, may be utilized with other kinds of liquid fuel.

It is the object of this invention to produce a burner of this character which is comparatively simple and inexpensive in construction, which is capable of being easily assembled and dismembered for inspection, adjustment and repairs, which is readily adjustable for either regulating the size of the flame or extinguishing the same, and which will yield the maximum heating efficiency for the amount of fuel consumed.

In the accompanying drawings:

Figure 1 is a side elevation of the preferred form of burner embodying my invention. Fig. 2 is a top plan view of the same. Fig. 3 is a vertical transverse section, on an enlarged scale, taken on line 3-3, Fig. 1. Fig. 4 is a fragmentary section taken on line 4-4, Fig. 1. Fig. 5 is a perspective view of the oil wells of the burner. Fig. 6 is a fragmentary horizontal section of one of the wicks and wick holders.

Similar characters of reference refer to like parts throughout the several views.

My invention is capable of being embodied in a burner which contains either a single oil well or a plurality of oil wells, but in the preferred organization which is shown in the drawings, two wells are employed which together with the wick supporting and flame controlling devices associated therewith constitute one unit, and it is to be understood that any number of such units may be arranged side by side for increasing the heating capacity of the burner to meet the requirements of a particular installation. The two oil wells or pots 1, 1, which are shown in the drawings are each of elongated form with openings at the top and arranged side by side with a vertical air supply passage 2 between the two wells. At one end these two wells are connected by a cross passage 3 so that the oil within the same will be distributed uniformly and

rise to the same height in both wells, this oil being supplied thereto in any suitable manner, for instance, by means of a pipe 4 leading into the lower part of the wells and provided with a valve 5 for regulating the admission of the oil. These two oil wells and the connecting passage between the same are preferably formed integrally of cast iron together with ears or lugs 6 on the exterior of the wells which support the flame adjusting and extinguishing devices and also with depending feet 7, 7 whereby the same may be supported on suitable ledges within the stove.

Arranged within each of these wells is a wick 30 whereby the oil is lifted from the well and burned at the upper end of the wick, also a holder for retaining the wick in place and means for retaining the wick holder yieldingly and removably in a central position lengthwise of the respective oil well. This wick may be constructed of any suitable absorbent material, but preferably asbestos inasmuch as the same is more durable and requires infrequent renewal. This wick is preferably constructed in the form of a flat right angle oblong plate which is arranged upright and lengthwise relatively to the well and has its lower part arranged within the well midway between opposite longitudinal walls thereof while its upper part projects above the same. In the drawings, this wick, is represented as being made of one continuous piece of material, but if desired, the same may be constructed of a number of sections assembled to form a complete wick, this last mentioned method permitting of utilizing smaller pieces of wicking to advantage and also enabling the wick to be repaired so as to maintain its full height or width and also restore the sharp corner at its burning edge when the same becomes worn and thus maintain a good even burning flame thereon.

The holder for the wick may be variously constructed but in the preferred form shown in the drawings, the same comprises a comparatively wide or high outer holding or supporting plate 8 of sheet metal which engages with the outer side of the wick and is provided at its lower edge with a horizontal flange 9 projecting laterally inward into engagement with the lower edge of the wick, a horizontal upper flange 10 projecting laterally inward from the upper edge of this

plate into engagement with the upper edge of the wick and two vertical flanges 11, 11, projecting laterally inward from opposite vertical edges of this plate into engagement with opposite vertical edges of the wick, as best shown in Figs. 2 and 6.

On its inner side the wick is engaged by an inner holding plate 12 of sheet metal which forms part of the wick holder, this last-mentioned plate being of substantially the same length as the outer holding plate 8 but of less width or height and extending from the lower edge of the wick upwardly but terminating at its upper edge short of the upper edge of the wick and the upper flange of the wide outer plate, so as to form a longitudinal flame-gap or slot 13 between the upper edge of the inner wick plate and the upper flange 10. Through this flame gap the upper part of the inner side of the wick is exposed and the flame produced by the burning oil at the upper edge of the wick passes laterally and upwardly from the wick to the parts which are to be heated. At its lower edge the narrow inner wick holding plate is provided with a horizontal flange 14 which projects laterally outward into engagement with the underside of the lower flange of the outer wick-supporting plate. The lower flange of the inner wick-holding plate engages with the bottom of the well and supports the wick holder and wick therein.

35 wick therem. The plates of the wick holder engage with opposite sides of the wick sufficiently firm to support the latter in an upright position and still permit the oil within the well to reach this wick through the joints between the same and holding plates, so that the
40 wick can lift the oil to the upper end of the wick where the same burns in the form of a flame on the laterally-exposed portion opposite the flame-gap. The wick-holder together with the wick, may be removably held within the well in a central position relative to the length thereof by any suitable means, but those which are shown in the drawings are preferred and comprise two vertically-bowed centering springs 15,
45 16, each of which is constructed of a metal plate and rests at its lower edge on the bottom of the well and bears against the lower part of the adjacent wick plate while its upper edge bears against the upper part of its respective wick plate and its intermediate part or crown bears against the inner side of the adjacent longitudinal wall of the well. When these plate springs are in place, the same are under tension so
50 60 as to hold the wick holder yieldingly in its central position but permit easy removal thereof when this becomes necessary for cleaning, inspecting or repairing of the burner. The outer centering spring is preferably comparatively high or long so that
65

the same bears against the upper part of the outer wick plate above the oil well and adjacent to the upper edge of this plate for retaining the same firmly in engagement with the wick, but the inner centering spring 70 is of less height or narrower than the outer centering spring and bears against the narrow inner wick plate along a line below the upper edge of the outer centering spring in order to provide the necessary clearance 75 space for the means which operate to regulate the flame.

The means for controlling the flame of each wick preferably comprises a shutter having the form of a plate 17 which is arranged vertically and lengthwise against the inner side of the inner wick plate, so that by raising or lowering this shutter plate the same engages slidingly with the inner wick plate and thereby permits of either covering the flame gap more or less for regulating the size of the flame, or totally extinguishing the same. 80 85

Various means may be employed for actuating the shutter plate of each of the wicks, but the means which are shown in the drawings are preferably so arranged that one adjusting mechanism serves the purpose of regulating both shutters of a pair of wicks. For this purpose, the wick holders are arranged so that their flame-gaps are arranged opposite each other and the upper edges of the shutters of both wicks are arranged horizontally in line and moved simultaneously up and down so that the flames of a pair of wicks of one unit will always burn uniformly and may be either increased or decreased simultaneously. The preferred means for effecting this adjustment of both regulating shutters comprises two vertically-swinging rock arms 18, 19 which are pivoted at their lower ends by means of horizontal transverse pins 20, 21 on the lugs 6 of the wells, while their upper ends are arranged between the opposite corresponding ends of the shutter plates and are pivotally connected therewith by means of pins or rivets 22 arranged on the end portions of the shutters and projecting from the corresponding ends of the shutters into opposite ends of a tubular eye 23 arranged at the upper ends of each rock arm. These means of attaching the shutters to the rock arms are not only very simple and inexpensive in construction but they also permit of easily and readily attaching these shutters to the rock arms as well as detaching the same therefrom. Owing to this pivotal connection of the rock arms with the well and the shutter plates, the latter are raised and lowered with a swinging motion and in order to permit the requisite horizontal movement of these arms and still preserve a compact construction of the burner, the front arm 18 is made straight while the

rear arm 19 is made of angular form, as shown in Fig. 1, so as to permit the same to swing over the connecting passage of the wells the requisite extent when lowering the 5 shutter plates.

The upper ends of the outer centering springs preferably engage the outer wick supporting plate on a line with the shutter plates, so that the wick plates are not only 10 pressed against opposite sides of the wick but also a yielding pressure is exerted between the narrow inner wick plates and the shutter plates for permitting the latter to properly control the flame gaps 15 of the wick holders. The narrow inner centering springs are however sufficiently short so that the shutters are able to move vertically the required extent without interfering with these inner centering springs. 20 Although the shifting of the rock arms and the shutters mounted thereon may be effected in many different ways, the means for this purpose which are shown in the drawings are simple and practical and as 25 there shown these means comprise a shifting rod 24 which extends through an adjacent wall of the stove and is connected at its inner end with the front rock arm 18 while its outer end is provided with a 30 handle 25 for manipulating the same.

When the upper corner of the wick adjacent to the flame gap becomes frayed or worn from use, the same may be trimmed off so as to restore it to its normal working condition, and if the same becomes worn to such an extent that the maximum efficiency is no longer obtainable, the wick may be reversed side for side so as to bring the upper, outer corner of the wick to the 40 burner position. In like manner the wick may be reversed vertically edge for edge and then again reversed side for side so that the two lower corners of the wick may be used successively adjacent to the flame-gap of the 45 wick holder for obtaining the best results. It is thus possible to utilize four burning surfaces on a wick before renewal of the same either in its entirety or at its upper and lower edge portions becomes necessary, 50 thereby effecting a considerable economy in maintaining the burner in its most effective condition.

As a whole, this burner is very compact and it is constructed of simple parts which 5 may be manufactured at low cost and easily assembled.

I claim as my invention:

1. An oil burner comprising an oil well, a wick holder arranged in said well and having two upright plates which are spaced apart, one of said plates being comparatively wide and provided at its upper edge with a laterally projecting horizontal flange and the other plate being relatively narrow and terminating at its upper edge at a dis-

tance from said flange forming a laterally opening gap therebetween; and a wick arranged between said plates and having one of its sides exposed through said gap.

2. An oil burner comprising an oil well, 70 a wick holder arranged in said well and having two upright plates which are spaced apart, one of said plates being comparatively wide and provided with laterally projecting flanges at its lower and upper horizontal edges and at its opposite vertical edges and the other plate being relatively narrow and terminating at its upper edge short of said upper horizontal flange on the wide plate forming a gap therebetween 80 and a wick arranged between said plates and having one side of its upper part exposed through said gap.

3. An oil burner comprising an oil well, a wick holder arranged in said well and having two upright plates which are spaced apart, one of said plates being comparatively wide and provided with laterally projecting flanges at its lower and upper horizontal edges and at its opposite vertical edges and the other plate being relatively narrow and terminating at its upper edge short of said upper horizontal flange on the wide plate forming a gap therebetween and provided 90 at its lower edge with a flange which engages with the underside of the lower flange of the wide plate, and a wick arranged between said plates and having one side of its upper part exposed through said gap. 95

4. An oil burner comprising an oil well, 100 a wick holder arranged in said well and having two upright plates which are spaced apart, a wick arranged between said plates, and means for holding said plates and wick removably in the central part of said well. 105

5. An oil burner comprising an oil well, a wick holder arranged in said well and having two upright plates which are spaced apart, a wick arranged between said plates, and means for holding said plates and wick 110 removably in the central part of said well comprising springs interposed between the outer sides of said plates and the walls of said well.

6. An oil burner comprising an oil well, 115 a wick holder arranged in said well and having two upright plates which are spaced apart, a wick arranged between said plates, and means for holding said plates and wick removably in the central part of said well 120 comprising two vertically bowed plate springs each of which bears with its upper and lower edges against the upper and lower parts of one of said wick holding plates while its crown bears against the adjacent 125 wall of said well.

7. An oil burner comprising an oil well, a wick holder arranged in said well and having two upright plates which are spaced apart, one of said plates being comparatively 130

- 4
- wide and provided at its upper edge with a laterally projecting horizontal flange and the other plate being relatively narrow and terminating at its upper edge at a distance 5 from said flange forming a laterally opening gap therebetween, a wick arranged between said plates and having one of its sides exposed through said gap, and means for retaining said holding plates and wick in a 10 central position relatively to said well comprising two vertically bowed plate springs interposed between the outer sides of said holding plates and the walls of said well and the plate spring bearing against the 15 wide holding plate being higher than the holding plate bearing against said narrow plate.
8. An oil burner comprising a well, a wick holder arranged in said well comprising upright plates spaced apart and constructed to form a laterally opening flame gap between the upper parts of said plates, a wick arranged between said plates and having one side exposed through said gap, and 20 a shutter movable across said gap.
9. An oil burner comprising a well, a wick holder arranged in said well comprising upright plates spaced apart and constructed to form a laterally opening flame gap between the upper parts of said plates, a wick arranged between said plates and having one side exposed through said gap, a 25
- shutter plate movable vertically across said gap, and vertically swinging rock arms pivotedly connecting said shutter plate with 35 said well.
10. An oil burner comprising a well, a wick holder arranged in said well comprising upright plates spaced apart and constructed to form a laterally opening flame 40 gap between the upper parts of said plates, a wick arranged between said plates and having one side exposed through said gap, a shutter plate movable vertically across said gap, vertically swinging rock arms pivotedly connecting said shutter plate with 45 said well, and a shifting rod connected with one of said arms.
11. An oil burner comprising two oil wells which are separated from each other by an 50 intervening air passage, two wick holders each arranged in one of said wells and provided with a laterally opening flame gap on its inner side which faces the other wick holder, wicks arranged in said wick holders 55 and exposed through said flame gaps, two regulating shutters slidable vertically on the inner sides of said wick holders across said flame gaps, and two vertically swinging arms pivoted at their lower ends on said well 60 and having their upper ends arranged between said shutters and pivotally connected therewith.

JOHN V. KRANEBIEL.
